[57] **CLAIM**

The ornamental design for a serving cart, as shown and
described.

DESCRIPTION

FIG. 1 is a perspective view of a serving cart showing
my new design;

FIG. 2 is a top plan view thereof;

FIG. 3 is a side elevational view thereof;

FIG. 4 is a front elevational view thereof, the rear eleva-
tional view being a mirror image of that shown; and
FIG. 5 is a bottom plan view thereof.
